UNITED STATES PATENT OFFICE.

CLAUDE M. GARLAND, OF CHICAGO, ILLINOIS.

GAS-PRODUCER.

1,114,979.

Specification of Letters Patent.

Patented Oct. 27, 1914.

Application filed December 15, 1913. Serial No. 808,738.

To all whom it may concern:

Be it known that I, CLAUDE M. GARLAND, a citizen of the United States, residing at Chicago, in the county of Cook and State of Illinois, have invented certain new and useful Improvements in Gas-Producers, of which the following is a full, clear, and exact description, reference being had to the accompanying drawings.

10 This invention relates to that type of gas producer in which a mixture of air with an endothermic reagent, such as steam or carbon dioxid, is forced through a bed of incandescent fuel whereby a combustible gas 15 is generated.

The general object of my invention is to provide a producer of this type, (for the gasification of bituminous coals and other fuels containing large quantities of volatile 20 matter in the form of hydro-carbon), in which the volatile matter contained in the fuel is distilled off at a low temperature which results in the formation of light oils and fixed or permanent gases, instead of 25 heavy pitch or tar. The distillation of the volatile matter at a low temperature also results in the destruction of the coking or caking properties of bituminous coals. The general result is, therefore, the production 30 of a producer for the gasification of bituminous coals which produces a gas essentially free from tar, of a high calorific value, due to the formation of fixed gases from the volatile matter, and easy to scrub. The de- 35 struction of the coking properties of the fuel makes the fuel easier to operate in the producer and the formation of fixed gases from the volatile matter raises the efficiency of the producer. The light oils formed may be re- 40 covered in scrubbing and can be used as valuable by-products. The low temperature distillation is accomplished in an upper or distillation chamber, by passing a non- 45 oxidizing gas at a temperature under 700° F., downward through the green fuel contained in the chamber. Superheated steam may be used as the gas or a portion of the gas generated from the coke remaining after distillation may be used. I prefer, however, 50 to use a mixture of the steam and the gas generated from the coke as this arrangement provides a means of securing a desirable temperature control over the mixture entering the distillation chamber, which will be 55 brought out later. A non-oxidizing gas is

used to prevent the combustion of the fuel which ignites at a very low temperature.

The results I accomplish in the manner herein described, reference being had to the accompanying drawing which forms a part 60 of these specifications, wherein: the figure represents a sectional elevation of a producer embodying my improvements, the section being taken on the center line.

The numeral 1 indicates a gas generating 65 chamber built up of the brick lining 3, shell 4 and top plate 5, supported in the seal ring 11 which is in turn mounted on the columns 10.

12 is a concrete water basin into which the seal ring 11 dips.

70 8 is a blast pipe provided with the hood 7 which prevents ash or coke from falling into the pipe 8.

9 is a flanged connection to which a blower may be attached for producing the blast.

75 On the top plate 5 is mounted the poke hole covers 6 and the outer wall 13 of the distillation chamber 2. The outer wall 13 is in the form of a steam generating space 42 and is provided with a water inlet 14, a 80 steam outlet 15 and a gage glass, not shown. Between the outer wall 13 and the inner wall 41 of the distillation chamber is an annular gas space 40, through which the gas passes to the gas exit 18. Communicating 85 with the distillation chamber 2, is the pipe 19 which communicates with the pipe 21 which in turn communicates with the gas space in the chamber 1 at 23.

22 is a valve located in the pipe 21.

90 24 indicates a steam nozzle extending into the pipe 19.

15 indicates a steam outlet pipe communicating with the steam space 42. In the pipe 15 is the cutoff valve 31. The pipe 15 communicates with the three-way valve 20 which is provided with the rotating plug 32 which is rigidly attached to the arm 33. Communicating with the three way valve 20 and the pipe 25 is the pipe 27. The pipe 26 communicates with the three way valve 20 and the superheating coil 39 which in turn communicates with the pipe 25 which communicates with the steam nozzle 24.

30 is a stop valve in the pipe 25.

105 28 is an outside steam supply pipe communicating with the steam outlet pipe 15.

29 is a stop valve located in the pipe 28.

110 37 indicates a thermostat of a type common to the art which is filled with a volatile

liquid and consists of a bellows 36, an arm 35 and a stem 38. The arm 35 is pivoted to the bracket 43 and the stem 38. To the arm 35 is pivoted a rod 34 which is in turn pivoted to the arm 33 of the valve 20.

16 indicates the cover plate of the chamber 2 on which is mounted the charging device 17.

The operation of the producer is as follows: An incandescent bed of coke is formed in the chamber 1, in the usual manner of starting up producers. After this is formed coke is charged through the charging device 17 until the coke reaches to within a foot 15 or two of the cover plate 16. A blast of steam and air is admitted at 9 to the blast pipe or twyer 8. The seal ring 11, by dipping into the water in the basin 12, prevents the escape of the blast. This blast 20 passes upward through the incandescent coke contained in chamber 1, thereby generating a combustible gas which passes up through the annular space 40 and out through the gas exit 18. The gas as it passes 25 up through the space 40 generates steam in the space 42, and also heats up the fuel contained in the chamber 2. The steam space 42 absorbs heat from the gases as they pass to the outlet 18 which prevents the gases 30 reaching too high a temperature in the space 40 which would cause the formation of tar from the volatile matter in the green fuel to be charged into the distillation chamber 2. As seen as steam is generated in 42, green 35 fuel is slowly charged through the device 17. The steam generated passes out through the pipe 15 and the valve 31 to the three-way valve 20, and through the three-way valve either direct to the steam nozzle 24 through 40 the pipe 27, or through the pipe 26, super-heating coil 39 and pipe 28 to the steam nozzle 24. From the steam nozzle 24 the steam issues in the form of a jet into the chamber 2. As the steam issues from the nozzle 24 45 it produces a suction in the pipes 19 and 21 and if the valve 22 is open a portion of the gas generated in the chamber 1 is drawn up through the pipe 21 into the pipe 19 and is discharged into the chamber 2 mixed with 50 the steam from the nozzle 24. In order not to generate an excessive amount of tar from the volatile matter a temperature between 400 and 700° F. should be maintained in the chamber 2, depending somewhat upon the 55 character of the fuel. The thermostat 37 which is common to the art is ordinarily made adjustable so that it may be set to maintain different temperatures. In the operation of the producer the steam leaving the 60 space 42 will not exceed 300° F.. The combustible gases leaving the chamber 1 may vary from 300° F. to 1200° F. depending upon the rate of working of the producer and other conditions. There would be times, 65 therefore, when the mixture of steam with

the combustible gas would not produce a temperature of 700° F. in the chamber 2. To avoid this the superheating coils 39 are used. If the temperature of the mixture fails to reach the temperature for which the 70 thermostat is set, 700° F. for example, the thermostat will cause the arm 33 to rise, thereby rotating the plug 32 which causes all of the steam to pass through the pipe 26 and superheating coils 39 located in the lining of chamber 1. These coils are consequently hot at all times due to the proximity of the incandescent coke. The plug 32 is shown in the position for sending all of the steam through the coils 39. If the temperature should rise above 700° F. the thermostat, acting through the bellows 36, arm 35 and reach rod 34, would depress the arm 33 thereby rotating the plug 32 of the valve 20, so that a portion or all of the steam 35 would pass through the pipe 27 to the steam nozzle 24. It will thus be seen that I have a convenient means of regulating the temperature of the gases entering the chamber 2, under all conditions.

In the operation of the producer, steam alone could be used by closing the valve 22 in the pipe 21. I prefer, however, to mix this with a portion of the combustible gas from chamber 1, which contains carbon-dioxide in small quantities. This constituent may, under proper conditions, unite with some of the decomposing hydro-carbon in the lower part of chamber 2 to form carbon monoxide, thereby enriching the gas generated. The gases from the chamber 1 could also be used alone. The steam, however, offers a convenient method of keeping the temperature constant and of forcing the mixture down through the green fuel in 100 the chamber 2.

The steam pipe 28 with valve 29 is to provide steam from an outside source, should the steam space 42 be damaged or cut out for repairs.

Having thus described my invention, I claim:

1. In a gas producer, a lower gas generating chamber, an upper distillation chamber, means for causing a mixture of air with an 115 endothermic reagent to pass upward through the said gas generating chamber, means for causing non-oxidizing gases to pass downward through the said distillation chamber, thermostatic means for maintaining the 120 temperature of the said non-oxidizing gases constant, and a gas exit for the gas and volatile matter generated.

2. In a gas producer, a lower gas generating chamber, an upper distillation chamber, 125 means for causing a mixture of air with an endothermic reagent to pass upward through the said lower gas generating chamber, whereby a combustible gas is generated, means for causing steam to pass downward 130

through the said upper distillation chamber, whereby the volatile matter is distilled off, means for controlling the temperature of the said steam, and a gas off-take for the 5 said volatile matter and the said combustible gas.

3. In a gas producer, a lower gas generating chamber, an upper distillation chamber, a communicating means communicating 10 with the gas space in the upper portion of the said lower gas generating chamber and with the interior of the upper part of the said upper distillation chamber, means for causing a mixture of air with an endothermic reagent to pass upward through the 15 said lower gas generating chamber whereby a combustible gas is generated, means for causing a portion of the said combustible gas to pass through the said communicating means and down through the said upper distillation chamber, whereby the volatile matter is distilled off, means for maintaining the temperature of the said portion of the 20 said combustible gas entering the said upper distillation chamber constant, and a gas exit for the said combustible gas and the said volatile matter.

4. In a gas producer, a lower chamber, a double walled upper chamber, the said upper chamber having a free opening into the said lower chamber, a steam generating space formed in the outer wall, and an annular gas passage formed between the inner and outer walls of the said upper chamber, 30 a gas exit communicating with the said annular gas passage, a pipe communicating with the upper portion of the said lower chamber and the upper portion of the said upper chamber, a steam nozzle in the said 35 pipe, a superheating coil in the lining of the said producer, a three-way valve, a pipe communicating with the said steam generating space and the said three-way valve, a pipe communicating with the said three-way valve and the said superheating coil, a 40 three-way valve and the said steam nozzle, a superheating coil in the lining of the said lower chamber, a pipe communicating with the said three-way valve and the said superheating coil, a pipe communicating with the 45 said superheating coil and the said steam nozzle, a thermostat located in the top of the said upper chamber, operating connections between the said thermostat and the said three-way valve, whereby the said thermostat operates the said three-way valve to maintain a constant temperature of the gases delivered to the said upper chamber, a twyer at the bottom of the said lower chamber, and a fuel charging device at the top of the said upper chamber, substantially as described.

In testimony whereof I have signed my name to this specification in the presence of two subscribing witnesses.

CLAUDE M. GARLAND.

Witnesses:

MYRTLE B. GARLAND,
J. G. PEIRSON.

pipe communicating with the said three-way valve and the said steam nozzle and a pipe communicating with the said steam nozzle and the said superheating coils.

5. In a gas producer, a lower chamber, a double walled upper chamber, the said upper chamber having a free opening into the said lower chamber, a steam generating space formed in the outer wall of the said upper chamber, an annular gas passage 55 formed between the inner and the outer walls of the said upper chamber, a gas exit communicating with the said gas passage, a pipe communicating with the upper part of the said lower chamber, and with the upper part of the said upper chamber, a steam nozzle in the said pipe, a three-way valve, a pipe communicating with the said steam generating space and the said three-way valve, a pipe communicating with the said three-way valve and the said steam nozzle, a superheating coil in the lining of the said lower chamber, a pipe communicating with the 60 said three-way valve and the said superheating coil, a pipe communicating with the 65 said superheating coil and the said steam nozzle, a thermostat located in the top of the said upper chamber, operating connections between the said thermostat and the said three-way valve, whereby the said thermostat operates the said three-way valve to maintain a constant temperature of the gases delivered to the said upper chamber, a twyer at the bottom of the said lower chamber, and a fuel charging device at the 70 top of the said upper chamber, substantially as described.
